ABSTRACT OF THE DISCLOSURE

In the separation of hydrophobic particles from hydrophilic particles, such as in coal preparation or the beneficiation of metallic ores, in a froth flotation cell, there is provided a static vortex inducer unit to which is fed a slurry of material to be separated and air to be dispersed therein, so that a vortex is induced in the slurry which is then discharged into the container, means also being provided to feed slurry from the container into further static vortex inducer means.

This invention is concerned with improvements in or relating to froth flotation.

In, for example, coal preparation and the beneficiation of metallic ores, material separation by froth flotation has been previously proposed. A froth is formed in a slurry of material to be separated and material rich in hydrophobic particles rises to the top of the slurry with the froth and material rich in hydrophilic particles falls to the bottom of the slurry. In the case of coal preparation the coal particles are hydrophobic and the dirt particles hydrophilic.

It is an object of the invention to provide an improved apparatus adapted for use in material separation by froth flotation.

The invention provides apparatus adapted for use in material separation by froth flotation comprising a container in which separation takes place in the operation of the apparatus, and a vortex inducer unit; the arrangement being such that in the operation of the apparatus a slurry of material to be separated is fed to the unit and a vortex is induced in the slurry which is then discharged from the unit to the container.

The invention also provides apparatus adapted for use in material separation by froth flotation comprising a container in which separation takes place in the operation of the apparatus, and a vortex inducer unit mounted in the container; the arrangement being such that in the operation of the apparatus the container contains a slurry of material being separated, a slurry of material to be separated is fed to the unit and a vortex is induced in the slurry which vortex acts to disperse air in the slurry which is then discharged from the unit to the container below the liquid level in the container.

The invention also provides apparatus adapted for use in material separation by froth flotation comprising a container in which separation takes place in the operation of the apparatus, and a plurality of separate slurry flow systems each of which comprises a vortex inducer unit mounted in the container; the arrangement being such that in the operation of the apparatus the container contains a slurry of material being separated, a slurry of raw material to be separated is fed to the vortex inducer unit of one system and a vortex is induced in the slurry which is then discharged from an outlet of the unit to the container, and slurry from the container is fed to the vortex inducer unit of the other system and a vortex is induced in said slurry which is then discharged from an outlet of the unit to the container.

2

The invention also provides apparatus adapted for use in material separation by froth flotation comprising a container in which separation takes place in the operation of the apparatus, and a plurality of separate slurry flow systems each of which comprises a vortex inducer unit mounted in the container; the arrangement being such that in the operation of the apparatus the container contains a slurry of material being separated, a slurry of raw material to be separated is fed to the vortex inducer unit of one system and a vortex is induced in the slurry which vortex acts to disperse air in the slurry which is then discharged from an outlet of the unit to the container, and slurry from the container is fed to the vortex inducer unit of the other system and a vortex is induced in the slurry which vortex acts to disperse air in the slurry which is then discharged from an outlet of the unit to the container.

The invention also provides a vortex inducer unit adapted for use in apparatus as set out in any one of the last preceding four paragraphs comprising a vortex chamber, a slurry inlet leading into the vortex chamber and a slurry outlet leading from the vortex chamber.

There now follows a description, to be read with reference to the accompanying drawings, of apparatus embodying the invention. This description is given by way of example of the invention only and not by way of limitation thereof.

In the accompanying drawings:

FIGURE 1 shows a diagrammatic side view of the apparatus;

FIGURE 2 shows an end view corresponding to FIGURE 1;

FIGURE 3 shows a side view of a vortex inducer unit of the apparatus;

FIGURE 4 shows a plan view corresponding to FIGURE 3; and

FIGURE 5 shows a flow diagram of a modified form of the apparatus.

The apparatus is adapted for use in material separation by froth flotation; the material comprises, for example, coal and dirt, or a metallic ore. The apparatus comprises a tank 20 in which separation takes place in the operation of the apparatus and which contains a body of slurry of material being separated, a plurality of generally submerged vortex inducer units 5, 18 mounted in the tank 20, two pumps 2, 15 and a feed tank 1; flow through the tank 20 in the operation of the apparatus is continuous and generally from left to right (FIGURE 1). The apparatus comprises two separate slurry flow systems and the units 5 form part of a first system and the units 18 form part of the other, second, system.

In the operation of the apparatus an aqueous slurry of raw material to be separated enters the feed tank 1 and is pumped by the pump 2 along a line 3 which leads into feed conduits 4 of the units 5. Frothing reagent and air are also supplied to the units 5; the units 5 act to emulsify the reagent in the slurry and disperse air in the slurry, froth being formed which rises to the top of the slurry in the tank 20 together with material rich in hydrophobic particles. Slurry is recycled from a lower portion of tank 20 along a line 11 the inlet of which is located generally underneath the units 5 adjacent the units 5; the line 11 and thus its inlet are adjustable both vertically and longitudinally and also transversely; the line 11 leads through an adjustable valve 12 into the line 3 upstream of the pump 2.

Slurry feed for the units 18 is withdrawn from the lower portion of the tank 20 into a line 13 extending into the tank 20 and the inlet of which is located to right (FIGURE 1) of the inlet of the line 11, and generally underneath the units 18 adjacent the units 18; the line 13 and thus its inlet are adjustable both vertically and longitudi-

nally and also transversely; the line 13 leads through an adjustable valve 14 into the pump 15 which pumps the slurry along a line 16 which leads into feed conduits 17 of the units 18. Frothing reagent and air are also supplied to the units 18; the units 18 act to emulsify the reagent and disperse air, froth being formed which rises to the top of the slurry in the tank 20 together with material rich in hydrophobic particles. The richness in hydrophobic particles of the material rising with the froth apparently decreases from left to right along the tank 20.

The apparatus also comprises chutes 8, 9 to either side (FIGURE 2) of the tank 20 and paddle wheels 7 arranged to rotate to deliver froth together with the material rich in hydrophobic particles into chutes 8, 9, the chutes 8 overlying the chutes 9. Said froth together with said material is delivered into the chutes 8, generally to the left of the units 18 and passes from the chutes 8 to a dewatering device (not shown) of known type where the froth is separated from the material rich in hydrophobic particles; said material then leaves the dewatering device as the product of the apparatus. Froth together with the material rich in hydrophobic particles is delivered into the chutes 9, to the right of the units 5 and is recycled into the line 3 upstream of the pump 2 through a line 10.

A slurry of tailings effluent which is rich in hydrophilic particles leaves the tank 20 through a line 19a which leads from the bottom of the tank 20; tailings effluent slurry also leaves the tank over a weir plate 22, which controls the level in the tank 20, and then through a line 19b which follows the weir plate 22.

Each vortex inducer unit 5, 18 (FIGURES 3 and 4) comprises a vertical circular cylindrical inner wall 29 which extends downwardly to a downwardly converging frustoconical inner wall 30 which terminates in a lower circular axial orifice 28; the upper end of the cylindrical wall 29 is closed by a horizontal circular wall 40; the walls 29, 30, 40 provide an inner vortex chamber 43 and the orifice 28 provides a slurry outlet leading from the chamber 43. Surrounding the walls 29, 30, 40 are similar, outer, walls 31, 33, 42 respectively; a generally annular chamber 44 is thus provided surrounding the chamber 43 and an axial annular outlet orifice 46 is provided surrounding the orifice 28. The feed conduit 4 or 17 of the vortex inducer unit terminates in a horizontal tangential inlet 23 which leads through the walls 31, 29 into the chamber 43; an injector nozzle 24 is provided in the inlet 23 and the injector nozzle 24 terminates flush with the wall 29. The walls 29, 30, 40, 31, 33, 42 are made of abrasion resistant material, e.g., cast basalt, synthetic plastics or rubber. A line 26 leads from the atmosphere into the inlet 23 and comprises a horizontal end portion 27 which terminates adjacent a mouth 59 of the nozzle 24. Two lines 32 lead from the atmosphere through the wall 42 into the chamber 44. The vortex inducer unit comprises a tube 25 comprising an upper end in communication with the atmosphere and a lower vertical end portion 48 which extends upwardly towards the orifice 28 and is co-axial with the orifice 28; the end portion 48 has an open end facing the orifice 28.

In the operation of the vortex inducer unit, slurry is fed continuously into the chamber 43 through the inlet 23 air being sucked in with the slurry from the line 26 by the action of the nozzle 24. It appears that a vortex is induced in the slurry in the chamber 43 and disperses air into fine bubbles dispersed in the slurry; the mixture of slurry and air is discharged at high speed from the orifice 28 below the liquid level in the tank 20 back into a lower portion of the body of slurry in the tank 20; also air is sucked through the lines 32, chamber 44 and orifice 46 by the mixture leaving the orifice 28, and air is sucked through the line 25. The frothing reagent is fed through the line 25. It appears that the slurry leaving the vortex inducer units acts to agitate and mix the slurry in the tank 20.

In a modified form of the apparatus (shown diagram-

matically in FIGURE 5) a set of three vortex inducer units 105 of a first flow system are connected to a feed line 130 in parallel and a group of nine vortex inducer units 118 of a second flow system are connected to a feed line 116 in parallel, being arranged in three sets 120 of three; the units of each set of three vortex inducer units 105, 118 are at the same longitudinal position in a tank 112, but the four sets are arranged at different longitudinal positions along the tank 112; otherwise the modified form of the apparatus resembles the apparatus described with reference to FIGURES 1 to 4.

Various other modifications of the apparatus and its operation are possible. For example, any of the following modifications may be made singly or in combination:

- 15 (a) The line 10 is closed, in which case the material rich in hydrophobic particles passing down the chute 9 is dewatered to give a low-grade product or added to the material passing down the chute 8, the combined material then being dewatered as a whole to give the product;
- 20 (b) Tailings effluent from the line 19a is recycled to the line 3;
- (c) Reagent is fed through the air line 26 of each vortex inducer unit; and
- 25 (d) Reagent is fed through one of the air lines 32 of each vortex inducer unit.

I claim:

1. Froth flotation apparatus comprising a container enclosing a single space for receiving a slurry of material being separated, a plurality of separate flow systems each 30 of which comprises, mounted in the container, static means for inducing a vortex in said slurry to disperse air therein, said static means having discharge means for then discharging said aerated slurry into said single space, means for supplying air to said vortex inducing means 35 for dispersal in said slurry by said vortex, means for feeding a slurry of raw material to be separated from a source external of said tank directly into the vortex inducing means of at least one system, and pump and conduit means in each said flow system for feeding slurry 40 from the container into the respective vortex inducing means of each said flow system, said conduit means having inlet means located in the lower portion of said container below and adjacent said discharge means of said respective vortex inducing means.

2. Apparatus according to claim 1 wherein said static 45 means comprises a vortex inducer unit, said unit comprising means forming a vortex chamber, a slurry inlet leading into the vortex chamber and a slurry outlet leading from the vortex chamber, the air supplying means leading into the inlet.

3. Apparatus according to claim 1 wherein said static 50 means comprises a vortex inducer unit, said unit comprising means forming a vortex chamber, a slurry inlet leading into the vortex chamber, and a slurry outlet leading from the vortex chamber, the air supplying means leading from the vortex chamber and in communication with the atmosphere at its other end.

4. Froth flotation apparatus comprising a container 60 adapted to contain a slurry of material being separated, a plurality of separate flow systems each of which comprises, mounted in the container, static means for inducing a vortex in a slurry of material to be separated to disperse air in the slurry and for then discharging said slurry to the container, means for supplying air to said vortex inducing means for dispersal in said slurry by said vortex, means for feeding a slurry of raw material to be separated into the vortex inducing means of at least one system, and means for feeding slurry from the container into the vortex inducing means of at least one other system, said 65 static means comprising a vortex inducing unit, said unit comprising means forming a vortex chamber, a slurry inlet leading into the vortex chamber and an axial slurry outlet orifice leading from the vortex chamber, the air supplying means forming an annular chamber surrounding the

vortex chamber and having an axial annular outlet orifice surrounding the outlet orifice of the vortex chamber, the annular chamber being in communication with the atmosphere.
